UNITED STATES PATENT OFFICE

92,378

DESIGN FOR A TOOL GRINDER

Lawrence L. Swingle, Prairie du Chien, Wis.

Application August 29, 1933, Serial No. 49,157

Term of patent 7 years

To all whom it may concern:

Be it known that I, LAWRENCE L. SWINGLE, a citizen of the United States, residing at Prairie du Chien, in the county of Crawford and State of Wisconsin, have invented a new, original, and ornamental Design for Tool Grinders, of which the following is a specification, reference being had to the accompanying drawing, forming a part thereof,

The figure is a perspective view of a tool grinder, showing my new design.

I claim:—

The ornamental design for a tool grinder, as shown.

LAWRENCE L. SWINGLE,
